(57) **CLAIM**

We claim the ornamental design for a tool for lifting boards or for dismantling pallets, as shown and described.

DESCRIPTION

FIG. 1 is a front perspective view of the tool for lifting boards or for dismantling pallets showing my design.

FIG. 2 is a front elevational view thereof;

FIG. 3 is a rear elevational view thereof;

FIG. 4 is a bottom plan view thereof;

FIG. 5 is a top plan view thereof; and,

FIG. 6 is a right side elevational view thereof.

The shaft is shown fragmentarily to indicate indeterminate length.
